EX

OR D 14,484

No. 14,484   DEC 11, 1883

UNITED STATES PATENT OFFICE.

ALBERT WAGNER, NEW YORK, N. Y., ASSIGNOR TO J. ESTEY & CO., OF BRATTLEBOROUGH, VERMONT.

DESIGN FOR AN ORGAN-CASE.

SPECIFICATION forming part of Design No. 14,484, dated December 11, 1883.

Application filed October 5, 1883. Term of patent 14 years.

To all whom it may concern:

Be it known that I, ALBERT WAGNER, a citizen of the United States, and a resident of the city, county, and State of New York, 5 have invented or produced a new and original Design for an Organ-Case, of which the following is a specification.

My design is clearly shown in the accompanying photographic illustration, in which 10 A designates the front board of the case; B, the key-board projection above the front board; C, the lid covering the key board or manual; D, the back board of the case, and E E the ends.

15 The general conformation of the case resembles that of ordinary cabinet-organ cases; but it differs from these in the particulars I will now set forth.

The front board, A, is divided, as usual, into 20 three panels, a a a, which I have ornamented by linear patterns b b b, as shown in the photograph—that is to say, in each end panel is a pattern composed of a square outline with square looped corners inclosing four smaller 25 squares with dots in their centers, and two parallel horizontal dividing-lines. At the middle of the upper and lower sides of the square exteriorly is a small square, and from these extend rays, as shown. The middle 30 panel is divided by a horizontal beaded strip, and the panel below this strip has a square central ornament flanked by triple-paired scrolls.

The front of the key-board projection B is 35 provided, as usual, with an open-work strip. This I form of one or two elongated openings filled in with semicircular arches c c, with spandrel openings above them, and divided by perpendicular bars into quadrants. In 40 each quadrant is a fan ornament, as shown.

I divide the upper surface of the lid C into three parts by two parallel bands, d, formed of a number of beads; but this feature is not new.

45 Above the lid C is another open-work panel, F, which is composed of two parallel horizontal rows of rectangular openings arranged to break joints or lap, as shown, and in each of which is an ornament, somewhat resembling a fleur-de-lis, the lower series being inverted.

The back board, D, extends considerably above the ends E, and at each end is provided with a pocket-like projection, G. These two pocket-like projections are ornamental and alike in size and appearance, and form a marked and novel feature of the design. Each projection G has two beaded bands across its front, an ornamental top to its front board, and a scalloped bottom, as shown. 55

On each corner of the back board D is mounted a scalloped ornament, e, with an outlined cross on its face, while on the center of the back is mounted a larger ornament, f, comprising a base-board with two elevated 60 scallop ornaments at the corners, a raised central ornament with an engraved front, a horizontal beaded band near the top, and a row of three disks or balls at top or bottom, two raised square bosses at the corners, each with 65 two disks or balls at its base, and each connected with the raised central ornament by a beaded strip, two engraved sprays below said beaded strips, and two parallel lines below these sprays with ornamented pendants. 75

Between the music-pockets is an ornament, g, composed of arched lines arranged concentrically, and the spaces between and within them ornamented by lines, as shown. The spandrels of the exterior arch are outlined. 80

On the elevated horizontal ends of the key-board projection are mounted platforms h h, and beneath these are short ornamental posts or balusters, and brackets i i.

Under the ends of the projection B are I- 85 shaped ornamental posts or columns H, the stems of which are square.

Having thus described my design, I claim as its novel features—

1. A design for an organ-case, having an open-work panel, F, above the lid of the case, consisting of two parallel horizontal rows of rectangular openings arranged to lap, and each opening provided with an ornament in the nature of a fleur-de-lis, substantially as 90 shown in the accompanying photograph.

2. A design for an organ-case, having two similar pocket-like projections, G G, mounted on its back D, substantially as shown in the accompanying photograph. 100

3. A design for an organ-case, having a back, D, elevated above the ends of the case, and

having ornaments *e*, *f*, and *g*, and pocket-like projections *G* mounted on the said back *D*, substantially as shown in the accompanying photograph.

5. A design for an organ-case, having platforms *h* *h*, with rows of short posts beneath their inner edges, and brackets *i* *i* arranged under them, substantially as shown in the accompanying photograph.

In witness whereof I have hereunto signed to my name in the presence of two subscribing witnesses.

ALBERT WAGNER.

Witnesses:

ARTHUR C. FRASER,
HERMAN WAGNER.
